UNITED STATES PATENT OFFICE.

CLARENCE A. SUMWALT, OF STEELING, KANSAS.

HAY-HARVESTING MACHINE.

1,070,359.

Specification of Letters Patent. Patented Aug. 12, 1913.

Original application filed June 28, 1912, Serial No. 706,437. Divided and this application filed October 10, 1912. Serial No. 725,027.

To all whom it may concern:

Be it known that I, CLARENCE A. SUMWALT, a citizen of the United States, residing at Sterling, in the county of Rice and State of Kansas, have invented certain new and useful Improvements in Hay-Harvesting Machines, of which the following is a specification.

The present invention comprises an improved machine for gathering hay, such as clover, alfalfa, or the like, and depositing the same on the field in piles or cocks, this application being a division of my co-pending application, Serial Number 706,437, filed June 28, 1912.

The invention involves primarily special pneumatic means for drawing the hay into a suitable casing and discharging the same upon a conveyer, or carrier, by which the material is subsequently deposited upon the ground.

This invention involves certain other general features of construction, the advantages of which will appear more fully upon reference to the following description and to the accompanying drawings, in which—

Figure 1 is a top plan view of a machine embodying the essential features of the invention. Fig. 2 is a vertical sectional view taken on line 2—2 of Fig. 1. Fig. 3 is a rear elevation of the machine as illustrated in Fig. 1. Fig. 4 is an elevation of a receiving spout embodied in the present invention. Fig. 5 is a vertical sectional view of the discharge spout. Fig. 6 is a side elevation of the machine as disclosed in Fig. 1.

Throughout the following detail description and on the several figures of the drawings, similar parts are referred to by like reference characters.

Describing the invention specifically and referring to the drawings, 1 denotes the frame of the machine which will be supplied with any suitable propelling means, 45 that illustrated comprising a motor 2 of any conventional construction. The motor 2 is operatively connected by suitable gearing 3 with the rear axle 4, the latter being supplied with ground wheels 5.

50 At its front portion, the frame 1 is supported by the caster wheels 6 mounted as usual upon rotative standards 7 at the upper ends of which are the rearwardly projecting arms 8. A drag link or rod 9 connects the arms 8 and is in turn operatively

attached to a shifting rod 10 at one end of the latter. The other end of the rod 10 has a rack 11 in mesh with the teeth of a spur gear 12 supported by the frame work of the machine, said gear 12 having bevel 60 teeth 13 in mesh with the bevel gear 14. The gear 14 is carried by the inclined steering shaft 15 having the hand wheel 16 at the end opposite the gear 14 and located adjacent to the seat 17. The seat 17 is conveniently mounted upon a platform 18 projecting from one side of the machine near its front portion, thus conveniently locating the operator to oversee the operation of the machine in the performance of its 70 functions.

Situated near the front end of the machine also, is a casing 19, preferably of cylindrical form in which is mounted a suction fan 20, the shaft 21 of which is operatively connected with the drive shaft of the motor 2 by means of a sprocket chain 22 or similar driving connection. In its top, the casing 19 is provided with a door 23 by which ready access may be had to 75 the interior of the casing wherein the fan 20 is located. A receiving spout 24 projects downwardly from the casing 19, the upper end of the spout being in communication with an opening in the bottom of the 80 casing while the lower end of the spout is composed of hinged sections 24' adapted to fold upward against the body of the spout when the machine is traveling over a field and the suction mechanism is not being 85 operated. Hooks 25 or similar fastenings may be employed to hold the sections 24' of the spout 24 elevated to clear any obstacles over which the machine may pass, and hooks 25' are used to operatively connect the sections.

Leading off from the casing and approximately at a tangent thereto is a pipe or conduit 26 which projects rearwardly of the frame of the machine and terminates in a 100 discharge spout 26', the walls of which are apertured. Suitable valves 27 in the form of sliding plates are mounted on the walls of the discharge spout 26', which opens downwardly above the conveyer 28, and said valves have handles 29' for ready manipulation of the same to close and open the apertures of the spout 26'. By reason of the provision of the valves 27, the apertures of the spout 26' may be regulated any size, 110

whereby to control the velocity of the air passing through the discharge opening in the bottom of the spout, for a purpose to be more fully presented hereinafter.

- 5 By reason of the arrangement of the receiving spout 24 of the casing 19, it will be apparent that while the machine is propelled over the field, the fan 20 may be driven at high speed to create sufficient suction at the spout 24 to draw into the casing, the hay to be harvested. As the hay is drawn through the spout 24 into the casing 19, it is driven or forcibly ejected from the casing 19 by the fan 20 into the conduit or pipe 26 and the blast of air created by the fan 20 is sufficient to force the material swiftly to the discharge end of the conduit. From the discharge spout 26' of the conduit 26, the hay falls downwardly upon a conveyer 28 and the valves 27 for the apertures of the spout 26' permit of escape of the air passing through the conduit 26 so that the hay may be discharged gently upon said conveyer.
- 10 25 The conveyer 28 which forms the subject-matter of the above-mentioned application comprises a frame 29 pivoted to the frame member 1, and adapted for slight swinging movement vertically whereby the wheels 30 may be brought into contact with the ground for operating the conveyer belt. The free end of the frame 29 is suspended from a counterbalance beam 32 by the bail 33, said beam being provided with an adjustable weight 34, whereby upon a certain amount of hay being deposited upon the belt, the frame 29 will be moved downwardly to bring the wheels 30 in contact with the ground. Upon the wheels contacting with the ground, the conveyer belt is immediately put into operation for depositing its shock of hay or other material on the ground, and after the belt is relieved of its load, the frame 29 assumes its normal raised position 45 due to the influence of the weight 34.

The function of the fan 20 is to a certain extent dual in that said fan not only draws or sucks the hay into the casing 19 but by mechanical contact with the material aforesaid, acts thereon to eject it into the conduit 26.

It is contemplated that certain of the minor features of construction of the invention may be modified in accordance with the

broad spirit of the improvements as hereinbefore presented and as permissible by reason of the scope of the appended claims.

Having thus described my invention, what is claimed as new is:

1. In a machine of the class described, the combination of a support adapted to be advanced over the ground, a casing carried by said support, a suction fan mounted in said casing, and a receiving spout at the lower portion of the casing and terminating proximate to the ground when in an operative position, said spout comprising hinged sections, each of which is independently movable into an upraised inoperative position to clear obstacles upon the ground. 70

2. In a machine of the class described, the combination of a support adapted to be advanced over the ground, a casing carried by said support, a suction fan mounted in said casing, a receiving spout at the lower portion of the casing and terminating proximate to the ground when in operative position, said spout comprising hinged sections, each of which is independently movable into an upraised inoperative position to clear 75 obstacles upon the ground, means for securing the sections together when the spout is in the operative position aforesaid, and other means for holding each of said sections in the upraised position. 80

3. In a machine of the class described, the combination of a support adapted to be advanced over the ground, a casing arranged thereon, a suction fan in said casing, a discharge conduit connected with the casing 90 and having a discharge spout provided with a discharge opening, said discharge spout being also provided with apertures adjacent to said discharge opening, and valve means controlling the operative area of said apertures, said means comprising apertured plates slidably mounted with respect to the spout, the apertures in said plates being registerable with the apertures in the spout, whereby movement of the plates will regulate the size of the openings through the spout. 95

In testimony whereof I affix my signature in presence of two witnesses.

CLARENCE A. SUMWALT.
